2 Claims

ABSTRACT OF THE DISCLOSURE

A guide assembly to be supported from a door and having a slide member supported therefrom for limit rectilinear reciprocation and engageable with a stop for defining one limit position of movement, the stop and the slide being interposed in an electrical signalling device circuit for closing the circuit when in contact with each other and the slide comprising an anchored end of a door night chain.

The alarm of the instant invention not only serves as a night chain for a door but also as a means for causing operation of an alarm signal should the associated door be opened to a position approaching the limit position defined by the associated night chain. The alarm is constructed in a manner such that it will comprise, in addition to an alarm actuating device, a suitable and durable anchor for one end of the associated night chain.

One end of the chain portion of the alarm is adapted to be secured to the door chain or a wall structure adjacent the door jamb and the alarm portion of the invention is adapted to be secured to the associated door. The alarm includes a guide portion which is stationarily secured to the door and a slide follower supported from the guide and shiftable between limit positions relative thereto. The adjacent end of the chain is anchored to the slide and means is provided for engagement by the slide to limit its movement in one direction. The slide and the means for limiting its movement in one direction include conductive portions thereof disposed in the electrical alarm circuit and which are operable to close the alarm circuit upon contact with each other.

The main object of this invention is to provide a night chain assembly including an alarm system incorporated therein which will be operative to render an audible signal in response to the associated door being opened to a point approaching the maximum open position allowed by the night chain.

Still another object of this invention is to provide an alarm assembly in accordance with the preceding objects and which may be readily installed.

Another object of this invention is to provide an alarm assembly including an electrically actuated alarm system and a self-contained source of electrical potential therefor.

Yet another object of this invention is to provide an alarm assembly for mounting on the associated door and which will render an audible alarm and thereby enable the associated door to sound the alarm given therefrom.

A final object of this invention to be specifically enumerated herein is to provide an alarm in accordance with the preceding objects which will conform to conventional forms of manufacture, be of simple construction and easy to use so as to provide a device that will be economically feasible, long lasting and relatively trouble-free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

2

FIG. 1 is a perspective view of the alarm operatively associated with the door and its jamb frame;

FIG. 2 is a perspective view of the alarm with the cover portion thereof illustrated in phantom lines;

FIG. 3 is an enlarged fragmentary vertical sectional view taken substantially upon a plane indicated by section line 3—3 of FIG. 1.

Referring now more specifically to the drawings the numeral 10 generally designates a conventionally hung horizontally swingable door and the reference numeral 12 designates a door jamb portion with which the free swinging edge portion 14 of the door 10 is operatively associated. The alarm is referred to in general by the reference numeral 16 and includes a chain 18 having one end anchored to an anchor loop 20 supported from a mounting plate 22 secured to the door jamb portion 12 in any convenient manner. The end of the chain 18 remote from the mounting plate 22 has a rigid S-loop 24 thereon for removable securement to an anchor loop 26 supported from the horizontal flange portion 28 of an L-shaped slide generally referred to by the reference numeral 30 also including a vertical flange portion 32.

The alarm 16 includes a strong base plate 34 of any suitable dielectric material such as plastic secured to the door 10 in any convenient manner such as by fasteners 36. The lower edge portion of the base 34 includes a horizontal slot 38 whose inner end opens into the lower end of a recess 40 formed in the face of the base plate 34 opposing the door 10 and the horizontal flange portion 42 of an L-shaped anchor bracket 43 constructed of stainless steel or any other strong material projects through the slot 38 and has its vertical flange portion 44 in the recess 40, the lower fasteners 36 extending through both the base plate 34 and the vertical flange portion 44 and with the face of the vertical flange portion 44 remote from the horizontal flange portion 42 flush with the face of the base plate 34 abutting the door 10.

A generally C-shaped guide 46 is provided and secured to the base plate 34 in any convenient manner such as by a rivet 48. The C-shaped guide 46 is secured to the base plate 34 above the horizontal flange portion 42 and the vertical flange portion 32 of the L-shaped slide 30 is slidably engaged with the guide 46.

The guide 46 may be constructed of any suitable dielectric material which can be injection molded and which has a low coefficient of friction. The horizontal flange portion 42 includes a slot 50 through which the anchor loop 26 extends and the S-loop 24 is removably engaged with the anchor loop 26 as hereinbefore set forth. The slide 30 is also to be constructed of a strong material such as stainless steel and it may be seen that the horizontal flange portion 28 of the slide 30 is held captive between the horizontal flange portion 42 of the bracket 43 and the adjacent end of the guide 46. The vertical flange portion 32 is accurately dimensioned so as to be frictionally retained in position within the guide 46 when the S-loop 24 of chain 18 is engaged with the anchor loop 26.

A pair of battery clips 54 and 56 are supported from the base plate 34 in any convenient manner such as by rivets (not shown) and a conventional battery 58 is supported between the clips 54 and 56, and the clip 54 is electrically connected to the horizontal flange portion 42 of the bracket 43 by means of a conductor 60 while the clip 56 is electrically connected to an electrically actuatable and audible signal alarm referred to in general by the reference numeral 62 by means of a conductor 64. The alarm 62 is also suitably mounted on the base plate 34 in any convenient manner such as by rivets (not shown) and the horizontal flange portion 28 of the slide 30 is electrically connected to the alarm 62 by means

of a conductor 66. Thus, when the horizontal flange portions 28 and 42 contact each other, the electrical circuit between the battery 58 and the alarm 62 is completed and the latter is electrically actuated.

In operation, after the door 10 has been closed, the S-hook 24 may be removably engaged from the anchor loop 20 (its storage portion) and engaged with the anchor loop 26 after the anchor loop 26 has been manually urged upwardly to insure that the horizontal flange portion 28 is spaced above the horizontal flange portion 42. Then, should any unauthorized person attempt to open the door 10, the chain 18 will be tensioned in a manner such that the slide 30 will be pulled downwardly into contact with the horizontal flange portion 42 completing the circuit to the signal 62 thereby electrically actuating the latter. Of course, the base plate 34 may be mounted on the door 10 in a horizontal position and substantially horizontally aligned with the mounting plate 22 and the use of the alarm 16 is not necessarily limited to use in conjunction with the door of a dwelling, but may also be utilized in other environments.

In order to completely enclose the components of the invention supported from the base plate 34, a closure cover referred to in general by the reference numeral 70 is provided and is removably secured over the face of the base plate 34 remote from the door 10 by means of a threaded fastener 72 removably and threadedly engaged with the threaded end of a fastener 74 supported from the base plate 34 and having its free threaded end portion projecting through an opening 76 in the cover assembly 70.

Although the alarm is primarily concerned with rendering a signal upon an unauthorized person attempting to open an associated door, window or other closure, it can also have incorporated therein any suitable means operative to actuate the alarm in response to an abnormal increase in temperature of the immediate surroundings, such as in the case of fire.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In combination with first and second relatively movable members supported for movement toward and away from each other, a movement limiting and signalling device comprising an elongated tension member, one end of said tension member being secured to one of said members, a mounting base secured to the other of said members, said base including guide means, an anchor member supported from said guide means for limited shifting relative thereto, said base including stop means

limiting movement of said anchor member relative to said guide means in one direction, an electrical alarm assembly supported from said base including an electrically actuatable alarm, a source of electrical potential and electrical circuit means electrically connecting said alarm with said source, said stop means and said anchor member including electrical contact defining portions serially disposed in said circuit means and engageable with each other upon movement of said anchor member to a limit position of movement in said one direction, said guide means comprising a generally C-shaped channel member, said anchor member including a portion thereof slidably and guidingly supported from said channel member for adjustable positioning therealong, said anchor member portion and said channel member including surface portions thereof disposed in frictional engagement with each other allowing shifting of said anchor member portion along said channel member but frictionally retaining said anchor member portion in position along said channel member, said stop means including a flange portion disposed generally normal to and which intersects with the path of movement of said anchor member along said channel member, said anchor member including an anchor element projecting toward said flange portion and receivable through said opening upon movement of said anchor member toward said limit position of movement in said one direction, the other end of said tension member being secured to the portion of said anchor element projecting through said opening.

2. The combination of claim 1 including a housing supported from said face in which said stop means, electrical alarm assembly, said guide means, said anchor member, a source of electrical potential and electrical circuit means are disposed, one wall of said housing generally parallel and being spaced slightly from the side of said flange portion facing in said one direction, said one wall of said housing having a second opening formed therein registerable with the opening formed in said flange portion and through which said anchor element also projects when said anchor member is in said limit position of movement in said one direction.
